HAIR CLIPPERS FOR TRIMMING HAIR TO DIFFERENT LENGTHS

Frank J. Vitale, Van Nuys, Calif.

Application July 14, 1955, Serial No. 521,994

3 Claims. (Cl. 30—210)

The present invention relates to the field of cutting devices, and more particularly to a clippers that is so positionable as to enable the barber to trim hair at longer lengths than has been possible heretofore by means of the presently available devices of this type.

Although clippers in a variety of styles and designs have been developed and marketed in the past, all of these devices have a common disadvantage in that they can only be used to trim hair within a relatively narrow range of lengths. When it is desired to trim hair to lengths longer than the cutting limits of these prior devices, the barber must necessarily resort to the use of scissors, which is not only a time-consuming operation, but requires a high degree of professional barbering skill. In contrast to the use of scissors in hair trimming, clippers can be used successfully for this purpose by a person of relatively limited skill, inasmuch as a portion of the clippers are in sliding contact with the hair-covered surface, and the cutting portion of the clippers can be maintained at a uniform distance therefrom.

The primary purpose in devising the present invention is to provide clippers that can be used to trim hair in the conventional close cropped manner provided by prior devices but will trim hair up to a first maximum length when they are held in a first position, and when disposed in a second position will trim the hair at a second maximum length.

A major object of the present invention is to provide clippers by means of which persons having a minimum of barbering skill may not only trim hair evenly in the short, conventional manner, but in longer lengths than is possible to achieve with previously available devices of this nature without the aid of scissors.

Yet another object of the invention is to provide a clippers which may be either manually or power-operated.

A still further object of the invention is to furnish a clippers which can be fabricated from standard commercially available materials, are attractively compact in appearance, and can be retailed at a sufficiently low price as to encourage their widespread use.

These and other objects and advantages of the invention will become apparent from the following description of a preferred form thereof, and from the drawing illustrating that form in which:

Figure 1 is a perspective view of the invention;

Figure 2 is a longitudinal cross-sectional view of the clippers shown in Figure 1;

Figure 3 is a transverse cross-sectional view of the invention taken on the line 3—3 of Figure 2;

Figure 4 is an enlarged fragmentary cross-sectional view of the hair cutting portion of the invention taken on line 4—4 of Figure 2;

Figure 5 is an enlarged fragmentary cross-sectional view of the actuating portion of the invention taken on line 5—5 of Figure 2;

Figure 6a is an end elevational view of the clippers shown in a first position;

2

Figure 6b is an end elevational view of the device shown in a second position; and

Figure 7 is a fragmentary cross-sectional view of the invention taken on line 7—7 of Figure 2.

- 5 Referring now to the drawing for the general arrangement of the invention, it will be seen to include a substantially rectangular hollow handle A in which an electromagnet or suitable motor B is disposed, which when actuated by alternating electric current causes an elongate 10 transversely toothed element C to reciprocate to cut hair with which it comes into contact. Element C, as can best be seen in Figure 2, is in slideable contact with a first transversely toothed guide D. When the invention is brought into sliding contact with a hair-covered surface 15 F in the manner illustrated in Figure 6a, the hair can be trimmed thereby to a length G, depending on the position to which the guide D is moved relative to the surface. Should it be desired to trim the hair at a longer length than possible when the invention is disposed as 20 shown in Figure 6a, a second guide E may be brought into sliding contact with the hair-covered surface whereby the hair may then be cut to a length H.
- In detail, the handle A is formed from two rigid 25 rectangular blocks 10 and 12. A centrally disposed recess 10a leads inwardly from one side 10b of block 10, and a second, narrower and deeper recess 10c extending outwardly from recess 10a leads to side 10d of the block. Block 12 also has a recess 12a that extends inwardly 30 from one side 12b thereof and a narrower extension 12c of recess 12a leads outwardly to side 12d of the block. Recess 10c is of such shape as to permit guide E to 35 snugly fit therein. Recess extension 12c is likewise adapted to snugly receive the rearward portion of guide D. Guides D and E are provided with several tapped bores 14 and 16 respectively on the rearward portions thereof, which bores are engaged by screws 18 and 20 that extend through bores formed in blocks 10 and 12. In Figure 2 it will be seen that guide E has a boss 22 formed on the outer end portion thereof that abuts against the 40 interior face of guide D. Boss 22 serves as a lateral spacer to maintain the desired relationship between guides D and E.
- A bore 24 extends transversely through boss 22 and is 45 in alignment with a tapped bore 26 formed in the outer portion of guide D. A screw 28 extends through bore 24 to engage bore 26 and hold guides D and E together as an integral unit. Blocks 10 and 12 are likewise 50 removably held together as an integral unit to form handle H, as screws 18 and 20 engage both blocks and guides D and E.
- Guide D is formed with a transverse convex exterior 55 surface 29. A plurality of teeth 30 are provided on the longitudinally extending sides of guide D, and the spaces 30a between teeth 30 are connected by grooves 32 formed in surface 29. Guide E likewise has a transverse convex exterior surface 34 and has a number of teeth 36 extending along the longitudinal sides thereof. Teeth 36 are separated by spaces 36a that are connected by grooves 38 formed in surfaces 34.
- 60 The elongate cutting element C is formed with a flat interior surface 38 that is in sliding contact with a flat inner surface 40 of guide D. Cutting element C has a transverse concave exterior surface 42 and also has a number of teeth 44 formed along the longitudinal edges thereof. Spaces 44a separate teeth 44, which spaces are 65 connected by grooves 46 formed in surface 42.
- Two longitudinally spaced cavities 50 are formed on the interior surface of guide E that are in alignment with two cavities 52 formed in cutting element C. Two compressed helical springs 54 have their end portions disposed 70 in cavities 50 and 52 and at all times maintain cutting element C in sliding contact with guide D. Longitudinal

alignment of cutting element C with guide D is preferably achieved by forming a recess 51 that extends substantially the length of the guide in which an elongate rib 53 on element C is slidably disposed.

The electro-magnet or motor B is of a type that upon actuation imparts a reciprocating motion to the cutting element C as is conventional in devices of this nature. Motor B receives alternating electric current by means of two insulated electrical conductors 60 and 62 as shown in Figure 7. The two conductors are connected to a domestic source of alternating current by a connector (not shown) and to a normally open electric switch 64 embedded in handle H. Switch 64 is provided with two insulated electrical conductors 66 and 68 extending to motor B. A pin 70 extends outwardly from switch 64 through the rearwardly disposed side wall 72 of handle H into an elongate recess 74 extending along this side wall as well as an adjoining forwardly extending side wall 76. An L-shaped bow spring 78 of slightly narrower width than recess 74 is disposed in same, and two screws 80 and 82 project through the end portions of the spring into handle H. The screws hold spring 78 outwardly from the surface 78a of the recess 74, with the interior surface of the spring being just in contact with the outer end of pin 70. When pressure is manually applied to the exterior spring surface 78a the spring is caused to bow inwardly, which inward spring movement is sufficient to cause pin 70 to move to a position where switch 64 is closed and electrical energy is supplied to motor B.

The use and operation of the invention is extremely simple. By applying pressure to the bow spring 78, the motor B is actuated, and the cutting element C caused to reciprocate relative to both the guides D and E. When it is desired to clip the hair closely, the invention is positioned as shown in Figure 6a, with the convex surface 29 then being in sliding contact with the hair-covered surface F. Rotational movement of the invention about its longitudinal axis permits the distance G to be varied from that of a close clip to the maximum length possible when the invention is in this position.

When it is desired to clip the hair at a length longer than that possible when the invention is held in the position shown in Figure 6a, the clippers are disposed as shown in Figure 6b. In this latter position, the convex face 34 of guide E is in slidable contact with the hair-covered surface F, and by rotational adjustment of the clippers, hair can be trimmed to a length H that is desired. Thus, by simply reversing the position of the device when in use, and without any mechanical adjustment thereto, the invention can be utilized to clip hair within a first range wherein the hair is cropped relatively short, and within a second range in which the hair is trimmed considerably longer.

Although the form of the invention herein shown and

described is fully capable of achieving the objects and providing the advantages hereinbefore mentioned, it is to be understood that it is merely illustrative of the presently preferred embodiment of the invention and is not to be limited to the details of construction as shown and described other than as defined in the appended claims.

The invention claimed is:

1. A hair clippers capable of being used to clip hair to lengths within a first range and alternately trim hair in longer lengths within a second range by reversing the position of said clippers, including: a first elongated guide having teeth on the longitudinal sides thereof; an elongate clipping member formed with teeth on the longitudinal sides thereof; a second elongate guide having teeth formed on the longitudinal sides thereof; means that maintain said first and second guides in parallel, laterally spaced relationship with one another; a handle from which said first and second guides project; means operatively associated with said handle, which means when actuated reciprocates said clipping member relative to said first and second guides; and means that maintain said clipping member in contact with said first guide and spaced from said second guide, with said first guide when disposed on a surface from which hair grows, permitting said hair to be clipped to a length within said first range, and said second guide when disposed on a hair-covered surface allowing said hair to be clipped to a desired longer length within a second range.

2. A hair clippers as defined in claim 1 in which said first guide is formed with a flat interior face that is slidably contacted by said clipping member, and an exterior surface of convex in transverse cross section having a plurality of grooves formed therein that extend between oppositely disposed tooth spacings, which grooves serve to guide hair into said tooth spacings on said first guide to be severed by said clipping member teeth at a length within said first range when said first guide is in slidable contact with a hair-covered surface.

3. A hair clippers as defined in claim 2 in which said first guide and clipping member are provided with slideable interlocking means that maintain them in longitudinal alignment one with the other.
